UNITED STATES PATENT OFFICE.

ROBERT W. SCOTT, OF PHILADELPHIA, PENNSYLVANIA, ASSIGNOR OF ONE-HALF TO LOUIS N. D. WILLIAMS, OF ASHBOURNE, PENNSYLVANIA.

PROJECTILE.

SPECIFICATION forming part of Letters Patent No. 733,920, dated July 14, 1903.

Application filed July 25, 1902. Serial No. 116,976. (No model.)

To all whom it may concern:

Be it known that I, ROBERT W. SCOTT, a citizen of the United States, residing in Philadelphia, Pennsylvania, have invented certain improvements in Projectiles, of which the following is a specification.

This invention relates mainly to that class of projectiles in which a mantle of relatively hard metal envelops a dense and heavy core of softer metal, the object of the invention being to so construct such a projectile as to retain all of the advantages due to the use of the hard-metal envelop, while at the same time taking advantage of greater ductility of the core in causing it to form a gas-check.

Certain features of the invention are also applicable to unjacketed projectiles, such as those used in field-guns or heavy ordnance.

In the accompanying drawings, Figure 1 is an enlarged sectional view of a projectile constructed in accordance with my invention. Fig. 2 is a similar view illustrating the hard-metal envelop locked to the soft core. Fig. 3 is a sectional view illustrating the application of my present invention to a projectile of the character set forth in my Letters Patent No. 694,575, dated March 4, 1902; and Figs. 4, 5, and 6 are other embodiments of my invention in conjunction with a projectile of this character.

In modern small-caliber rifles which impart extremely high velocities to the projectiles it has been found necessary to provide the lead or other soft-metal core 1 with a mantle 2, composed of a mixture of copper and nickel or some other relatively hard metal or alloy, because, owing to the high velocity imparted to the projectile and the high rate of rotation necessitated by the small caliber, a soft-metal projectile would not be rotated by the rifling, but would "jump" the lands. It has been found, however, that while the hard-metal envelop serves well its desired purpose of imparting rotating movement to the projectile, it also lessens the capacity of said projectile to expand under the pressure of the gases of combustion, so that these modern projectiles usually have a greater diameter in excess of caliber than the old soft-metal projectiles;

but even when the diameter of the projectile equals the caliber plus the depth of two of the grooves a serious escape of gas occurs before the inertia of the projectile is overcome.

In carrying out my present invention I do not extend the mantle of the projectile to the rear end of the same, but discontinue it some distance in advance of said rear end, so as to provide in the rear of the mantle a portion of soft metal, which can be readily expanded by the pressure of the gases of combustion, so as to serve as a gas-check without in any way affecting the function of the hard-metal envelop as a means of imparting rapid rotation to the projectile.

In Fig. 1 of the drawings this soft-metal rear portion of the projectile is represented at 3, the same being of the full diameter of the projectile and having, if desired, a lubricating cannelure 4 and being also by preference recessed at the rear, as shown at 5, so as to facilitate its expansion by the action of the gases of explosion upon it.

The portion of the projectile between the lines α and β is practically parallel and of the proper diameter to accurately engage with the lands and grooves of the rifling. Consequently when a projectile of this character is fired from the gun such engagement of the hard-metal envelop with the rifling causes rotation of the projectile in the same manner as in a projectile in which the envelop completely incases the soft-metal core. Hence by the time the portion 3 of the projectile reaches the rifling said projectile has acquired its rotating movement, and the soft-metal rear portion 3 of the projectile is simply caused to follow the rifling, the latter exerting no side-wise strain upon said soft metal, and hence having no tendency to shear the same or interfere in any way with the performance of its proper function as a gas-check.

In order to insure the retention of the soft-metal core within the mantle during the flight of the projectile, a cannelure may be provided in the core, into which the rear edge of the mantle may be turned, as shown at 6 in Fig. 2, this construction being resorted to as a safeguard only, however, as it is consid-

ered impossible for the two parts of the projectile to separate so long as the entrance of gas between the core and the mantle is prevented, and such entrance will be closed by the shoulder 7.

In Fig. 3 I have illustrated my invention as applied to a projectile of the character set forth in my Patent No. 694,675—that is to say, one in which the projectile has a flange 8 overlapping the forward end or mouth of the cartridge-casing 9. The flange 8 is formed by a projecting portion of the soft-metal core 1, and the forward end of the cartridge-casing is crimped into a cannelure 10, formed in said core; but such crimping of the forward end of the casing into the cannelure can be dispensed with if the said forward end of the casing is reduced in diameter to receive the flange 8, as shown in Fig. 4.

In the construction shown in Fig. 5 the mantle 2 has a bell shape or flare 11 at its rear end, so as to overlap the flange 8 of the core, instead of meeting the same with an abrupt shoulder, as shown in Figs. 3 and 4, said flaring portion of the mantle in this case constituting the gas-check, and the flange 8 of the core preventing any access of gas to the space between the mantle and core.

In the construction shown in Fig. 6 the core 30 is in the first instance formed with a straight flange, and the forward end of the cartridge-casing has a beveled edge, so that when the projectile is seated in the cartridge-case by the loading-machine this beveled edge will 35 cut into the soft-metal flange 12, and thus cause the latter to overlap the forward edge of the flange.

Having thus described my invention, I claim and desire to secure by Letters Patent—

40 1. A projectile having a soft-metal core provided with a mantle of harder metal discontinued in advance of the rear end of the projectile so as to provide a band of soft metal in the rear of the mantle to form a gas-check, 45 the mantle having a portion for engaging the rifling and imparting rotative movement to the projectile, substantially as specified.

2. A projectile consisting of a soft-metal core, and a mantle of harder metal discontinued in advance of the rear end of the projectile, said soft-metal core having, in the rear of the mantle a flange for overlapping the mouth

of the cartridge-casing, substantially as specified.

3. A gun-cartridge consisting of a projectile 55 having a soft-metal core and a mantle of harder metal discontinued in advance of the rear of the projectile, a flange projecting from said soft-metal core in the rear of the mantle, and a casing the mouth of which is overlapped 60 by said flange, substantially as specified.

4. A projectile consisting of a soft-metal core, and a mantle of harder metal discontinued in advance of the rear end of the projectile, said soft-metal core having a flange for 65 overlapping the mouth of the cartridge-casing, and the mantle having a flaring rear portion overlapping said flange, substantially as specified.

5. A gun-cartridge consisting of a projectile 70 having a soft-metal core, and a mantle of harder metal discontinued in advance of the rear end of the projectile, the core having a projecting flange, 75 and the mantle having a flaring portion overlapping said flange, in combination with a casing having a mouth portion reduced in diameter and overlapped by said flange, substantially as specified.

6. A gun-cartridge having a projectile with soft-metal core, a mantle of harder metal discontinued in advance of the rear end of the projectile, said core having a projecting flange, and the mantle having a flaring portion overlapping said flange, in combination with a casing having a mouth portion overlapped by 80 the flange of the core, substantially as specified. 85

7. A gun-cartridge consisting of a projectile having a soft-metal core, and a mantle of harder metal discontinued in advance of the rear end of the projectile, said core having a 90 projecting flange, and the mantle having a flaring rear end overlapping said flange, in combination with the cartridge-casing having a mouth portion reduced in diameter and overlapped by the flange of the core, substantially as specified. 95

In testimony whereof I have signed my name to this specification in the presence of two subscribing witnesses.

ROBERT W. SCOTT.
